CLAIM

The ornamental design for a printer stand, as shown and described.

DESCRIPTION

FIG. 1 is a front, left and top perspective view of a printer stand, showing our design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is an enlarged view of portion 9 shown in FIG. 1. The dash-dot broken lines in the drawings illustrate the portions of the printer stand which form no part of the claimed design. The dash-dot broken lines represent the bounds of the enlarged view and form no part of the claimed design.

1 Claim, 9 Drawing Sheets(56)
